UNITED STATES PATENT OFFICE

149,057

DESIGN FOR A FONT OF TYPE OR SIMILAR ARTICLE

Berthold Goldsmith, Jr., Woodmere, N. Y., assignor to Botany Mills, Inc., Passaic, N. J., a corporation of New Jersey

Application January 17, 1947, Serial No. 136,217

Term of patent 14 years

(Cl. D64—12)

To all whom it may concern:

Be it known that I, Berthold Goldsmith, Jr., a citizen of the United States of America, residing in Woodmere, county of Nassau, and State of New York, have invented a new, original, and ornamental Design for a Font of Type or Similar Article, of which the following is a specification, reference being had to the accompanying drawing, forming part thereof in which Figs. 1 and 2 illustrate face views of a font of type or similar article, showing my new design.

I claim:

The ornamental design for a font of type or similar article, substantially as shown.

BERTHOLD GOLDSMITH, JR.
